UNITED STATES PATENT OFFICE.

JOHN B. CONRAD, OF CHICAGO, ILLINOIS.

DESIGN FOR A STORAGE-BATTERY PLATE.

SPECIFICATION forming part of Design No. 32,366, dated **March 20, 1900.**

Application filed February 14, 1900. Serial No. 5,228. Term of patent 7 years.

To all whom it may concern:

- Be it known that I, JOHN B. CONRAD, a citizen of the United States, and a resident of Chicago, in the county of Cook and State of Illinois, have invented and produced a new and original Design for Storage-Battery Plates, of which the following is a specification, reference being had to the accompanying drawings, forming a part thereof.
- 10 In the drawings, Figure 1 is a side view of a storage-battery plate, showing my new design. Fig. 2 is a transverse vertical section thereof.
- As shown in the drawings, the leading or 15 material feature of my design consists of the cross-bars $a a'$ of the oblong plate A, which are triangular in cross-section and are arranged alternately, bars a being on one side or face of plate A and bars a' on the other.
- 20 The apices of the triangular bars $a a'$ face inwardly and extend to the median plane of the plate between the broad faces thereof, the bases of bars $a a'$ being respectively flush with the opposite faces of the plate. The

horizontal end portions $b b$ of the plate are 25 connected by vertical partitions $c c$ intersecting and connecting the cross-bars $a a'$ and arranged at suitable distances apart. These bars a are separated a distance corresponding to a little more than the width of their 30 bases or outer faces, and the bars a' are similarly separated, bars a' being arranged alternately with bars a .

On the upper end of plate A is a projecting lug D, the lower edges of which are gradually 35 merged into the plate by curves, as shown.

Having thus described my design, what I claim is—

The design for a storage-battery plate substantially as herein shown and described. 40

In testimony whereof I have signed my name to this specification in the presence of two subscribing witnesses.

JOHN B. CONRAD.
